GEOGRAPHICAL TIME CALCULATOR

Bengt Olof Mellberg, Nybodagatan 10^{IV},
S-17142 Solna, Sweden

Filed May 4, 1973, Ser. No. 357,516

Claims priority, application Sweden Nov. 8, 1972

Term of patent 14 years

Int. Cl. D19—99

U.S. Cl. D64—11 B

FIG. 1

FIG. 2

FIG. 4

FIG. 3

FIG. 5

FIG. 6

FIG. 1 is a front elevational view of a geographical time calculator showing my new design;

FIG. 2 is a rear elevational view thereof;

FIG. 3 is a side elevational view thereof, the other side being identical;

FIG. 4 is a front elevational view of an inner sliding insert;

FIG. 5 is a front elevational view showing the insert of FIG. 4 offset to the left; and

FIG. 6 is a front elevational view showing the insert of FIG. 4 offset to the right.

I claim:

The ornamental design for a geographical time calculator, as shown and described.
